UNITED STATES PATENT OFFICE.

ROBERT L. UNDERWOOD, OF TOLEDO, OHIO, ASSIGNOR TO AMOS H. BOARDMAN, OF SAME PLACE.

FUEL-OIL BURNER.

SPECIFICATION forming part of Letters Patent No. 524,289, dated August 7, 1894.

Application filed September 20, 1893. Serial No. 486,048. (No model.)

To all whom it may concern:

Be it known that I, ROBERT L. UNDERWOOD, a citizen of the United States, residing at Toledo, in the county of Lucas and State of Ohio, have invented a new and useful Improvement 5 in Fuel-Oil Burners, of which the following is a specification, reference being had to the accompanying drawings.

My invention relates to apparatus for burning cheap mineral oil in stoves and furnaces for heating purposes, and consists of a peculiarly constructed heater for heating the oil and converting it into a gas or vapor in connection with other parts as more fully pointed 15 out hereinafter.

In the accompanying drawings Figure 1 is a perspective view of my burner connected to a supply tank. Fig. 2 is a plan view of the heater. Fig. 3 is an end elevation of the 20 heater. Fig. 4 is a sectional plan view at *a b* Fig. 3 of the heater. Fig. 5 is a sectional elevation at the line *e f* Fig. 2 of the heater. Fig. 6 is a longitudinal sectional elevation at *c d* of the heater and jet pipes.

Similar letters and numerals of reference 25 refer to similar parts throughout the several views.

A closed tank *T* contains the supply of oil and is made large enough to hold a barrel or 30 more of oil. The tank *T* may be located on the same floor as the stove in which the burner is used or below it.

An opening *12* in the top of the tank is used for filling the tank and is closed by the 35 threaded plug *13*. An air pipe *14* admits air under pressure from an ordinary hand pump. The air is pumped in above the oil to create a sufficient pressure to drive the oil through the pipes and heater. A pressure gage *15* indicates the air pressure at any time. A pipe 40 *18* conveys the oil from the tank *T* to the heater *H* and has a valve *17* to regulate the flow of oil for a large or small fire. The heater *H* is a hollow casting having an opening *24* at 45 one end to receive the pipe *18*, and an opening *25* in the top to receive burner pipe *19*.

Within the heater or retort there is an essentially open ended rectangular partition, which divides the interior of the heater or retort 50 into a series of passages, so that when the oil enters at *24*, it is compelled to pass down the

sides of the heater and then back again to the center before it passes out through the pipe 55 *19*. In the upper face of the heater or retort are produced two depressions *36* and *37* upon opposite sides of the central line, for the purpose of collecting the oil for an initial lighting.

A pipe *19* conveys the gas and vapor from the heater *H* to the branch pipes *20* and *21* which have each a small hole on the lower 60 side *33* and *34* through which the gas and vapor escape in currents which strike the central apex *40* of the heater *H* and are deflected in each direction and made to fill the combustion chamber of the stove or furnace. 65

In operation the heater *H* is placed in the fire box of a stove or furnace and connected to the tank *T* which may be in an adjoining room or in the basement below. An amount of air is pumped into the tank *T* above the 70 oil sufficient to create a pressure of about fifteen pounds per square inch and the valve *16* is closed, the valve *17* is then opened and a small amount of oil allowed to flow through into the basins *36* and *37* on the heater *H*. This 75 oil is lighted, and as it burns it heats the heater *H* until it causes an oil vapor to issue from the openings *33* and *34*.

The heater *H* is made sufficiently large so that the flame in contact with its upper surface will generate gas or vapor as fast as it 80 can issue through the openings *33* and *34* thus producing the gas as it is used.

This burner is meant to be used to burn oil that is free from sediment, but in case there 85 should be a small amount of sediment in the oil or a slight deposit of carbon as the oil is vaporized the opening in the heater is so large and consequently the flow of oil and vapor so slow, that any sediment may settle to the bottom and remain there for a time or until 90 cleaned out.

I have shown my burner with two branch pipes *20* and *21* each having a small hole in the lower side from which issue the jets of gas. 95 But I do not wish to confine myself to two branch pipes and two jets for the device may be used with more or less without essentially changing the mode of working.

Having described my invention, what I 100 claim, and desire to secure by Letters Patent, is—

In a fuel oil burner, a heater or retort having depressions in its upper face, supply and burner pipes secured in the same, said burner pipe extending above the heater and branched 5 horizontally in opposite directions, said branch pipes having apertures upon the under side of the same.

In testimony that I claim the foregoing I

have hereunto affixed my signature, this 16th day of March, 1893, in the presence of two to subscribing witnesses.

R. L. UNDERWOOD.
